CLAIM

The ornamental design for a facial cleansing brush, as shown and described.

DESCRIPTION

FIG. 1 is a perspective view of a facial cleansing brush, showing my design.

FIG. 2 is a front elevation view thereof.

FIG. 3 is a rear elevation view thereof.

FIG. 4 is a left side elevation thereof.

FIG. 5 is a right side elevation thereof.

FIG. 6 is a top plan view thereof.

FIG. 7 is a bottom plan view thereof.

FIG. 8 is an enlarged view of an area labeled 8 in FIG. 1.

FIG. 9 is an enlarged view of an area labeled 9 in FIG. 2.

FIG. 10 is an enlarged view of an area labeled 10 in FIG. 4.

FIG. 11 is an enlarged view of an area labeled 11 in FIG. 5.

FIG. 12 is an enlarged view of an area labeled 12 in FIG. 6; and,

FIG. 13 is an enlarged view of an area labeled 13 in FIG. 7. The indicia on the buttons shown in broken lines in FIGS. 1, 2, and 7 depict environmental structure. The circles surrounding the enlarged, detail views and demarking the portions of the figures from which the enlargements were extracted are boundaries. None of the drawing elements shown in broken lines forms a part of the claimed design.

1 Claim, 13 Drawing Sheets
